UNITED STATES PATENT OFFICE.

WILLIAM TAYLOR NOAH, OF ELON COLLEGE, NORTH CAROLINA.

SPINDLE-DRIVING MECHANISM.

No. 874,614.

Specification of Letters Patent.

Patented Dec. 24, 1907.

Application filed March 30, 1907. Serial No. 365,575.

To all whom it may concern:

Be it known that I, WILLIAM TAYLOR NOAH, a citizen of the United States, residing at Elon College, in the county of Alamance and State of North Carolina, have invented a new and useful Spindle-Driving Mechanism, of which the following is a specification.

10 This invention relates to spindle driving mechanism for spinning machines of that general class shown and described in United States Letters Patent granted to me on the 17th day of Aug. 1897 under No. 588235.

15 The object of the invention is to improve and simplify the construction of the bolster and its associated parts and further to provide a novel form of step or bearing for the lower end of the spindle.

20 A still further object is to generally improve this class of devices so as to increase their utility, durability and efficiency.

25 Further objects and advantages will appear in the following description, it being understood that various changes in form, proportions and minor details of construction may be resorted to within the scope of the appended claims.

30 In the accompanying drawings forming a part of this specification: Figure 1 is a vertical sectional view of the improved spindle driving mechanism. Fig. 2 is a transverse sectional view taken on the line 2—2 of Fig. 1. Fig. 3 is a perspective view of the bolster detached. Fig. 4 is a similar view of 35 the step detached.

Similar numerals of reference indicate corresponding parts in all of the figures of the drawings.

40 The improved bolster forming the subject matter of the present invention is supported in position on the usual bolster rail 5, the latter being provided with a circular opening 6 for the reception of the reduced upper end 7 of the bolster, as shown: The bolster 45 is formed with an intermediate enlargement 8 defining an annular shoulder 9 which bears against the lower face of the bolster rail 5 and is retained in engagement with the rail by means of a clamping nut 10 which engages the terminal threads on the reduced extension 7 of said bolster. The enlargement 8 is formed with a cut away portion or opening 11 and depending from the bol-

ster at said opening and preferably formed integral therewith is a cylindrical member 55 or extension 12 the exterior walls of which are threaded, as indicated at 13.

Disposed within the cylindrical member 12 is a step 14 provided with a longitudinal bore 15 for the reception of the adjacent end 60 of the spindle 16, the latter being provided with a conical terminal for engagement with a correspondingly shaped seat 17 formed in the base of the step, as shown. The step 14 is provided with spaced annular flanges or 65 disks 18 and 19 defining an intermediate chamber 20 for the reception of oil or other lubricant. Extending transversely across the bottom of the cylindrical extension 12 is a cap or closure 22 which is threaded for engagement with the threads 13 so that the cap may be readily detached from the extension when it is desired to remove the step and spindle. The step 14 is provided with a central depending lug or boss 23 and surrounding said boss and interposed between the cap 22 and the bottom of the step 14 is a yieldable gasket or washer 24. The upper disk 19 is spaced a short distance from the adjacent upper edge 25 of the extension 12 70 thereby to form a cup 26 for the reception of a quantity of oil there being an opening 27 formed in the disk 19 through which the oil may pass from the cup 26 into the oil chamber 20. The walls of the step are inclined or 75 beveled on each side of the disk 19 to form a groove 28 which serves to guide the oil through the opening 27 into the chamber 20, there being an opening or recess 29 formed in said step and communicating with the bore 80 15 so that the oil in the compartment 20 may enter said bore and lubricate the bearing 17.

Secured to the spindle above the step 14 is a whirl or pulley 30 provided with an extension or collar 31, which latter is welded, 95 shrunk or otherwise rigidly secured to the spindle so as to rotate with the latter. The whirl 30 is disposed at the opening 11 and is driven by a friction disk or driver 32 which latter is keyed on an operating shaft 33 and 100 yieldably supported in engagement with the whirl by means of a coiled spring 34. The friction disk 32 is provided with an annular flange having a seating groove formed therein for the reception of a gasket or cushion 36 105 which may be formed of rubber, leather or

other suitable material and which frictionally engages the periphery of the whirl, as shown. The spindle 16 is centered with respect to the bolster by means of an upper bearing or gland 37 which engages a correspondingly shaped recess formed in the reduced extension 7 of said bolster. The whirl 30 is preferably formed with an interior recess for the reception of the tubular body portion 41 of the step, as shown. It will thus be seen that when the oil or other lubricant is introduced in the cup 26, the latter will flow through the openings 27 and 29 into the bore 18 and thus thoroughly lubricate the bearing 17. It will also be observed that by removing the cap 22 the step spindle and its associated parts may be withdrawn from the bolster through the threaded end of the latter, said cap not only forming a support for the step but also serving as a closure so as to effectually exclude the entrance of dust and dirt to the bearing.

Having thus described the invention what is claimed is:

25 1. The combination with a bolster rail, of a bolster secured to the rail and having an opening formed in one side thereof, a step carried by the bolster, a spindle journaled in the step and provided with a whirl disposed at the opening of the latter, and a cap secured to one end of the bolster and forming a support for the step:

35 2. The combination with a bolster rail, of a bolster secured to said rail and having an opening formed in one side thereof, a step carried by the bolster and provided with spaced disks forming an intermediate oil chamber, there being an opening formed in the upper disk and communicating with the oil chamber, a spindle journaled in the step and provided with a whirl disposed at said opening, and a cap secured to one end of the bolster and forming a support for the step.

3. The combination with a bolster rail, of a bolster secured to the rail and having its lower end threaded and one side thereof provided with an opening, a step disposed within the bolster, a spindle journaled in the step and provided with a whirl disposed at the opening in the bolster, a cap engaging the threads on the bolster and forming a support for the step, and a washer interposed between the cap and step.

4. The combination with a bolster rail, of a bolster secured to the rail and having an opening formed in one side thereof, a cylindrical extension depending from the bolster at said opening and having its exterior walls threaded, a step disposed within the cylindrical extension and provided with spaced disks defining an intermediate oil chamber, a spindle journaled in the step and provided with a whirl disposed at the opening in the bolster, and a cap engaging the threads on

the cylindrical extension and forming a support for the step, there being a recess in the step forming a source of communication between the bearing and oil chamber.

5. The combination with a bolster rail, of a bolster secured to the rail and having an opening formed in one side thereof, a step disposed within the bolster at one end thereof, a bearing carried by the opposite end of the bolster, a spindle passing through said bearing and journaled in the step, a whirl carried by the spindle, a cap detachably secured to the bolster and forming a support for the step, an operating shaft, and a friction disk having a cushioned face for engagement with the whirl.

6. The combination with a bolster rail, of a bolster secured to the rail and provided with oppositely disposed concentric extensions, there being an opening formed in the bolster intermediate said extension, a step disposed within one of the extensions, a spindle journaled in the step and arranged concentric with the walls of both of the extensions, a cap detachably secured to one end of the bolster and forming a support for the step, a whirl secured to the spindle, an operating shaft, and means carried by the operating shaft and engaging the whirl for rotating the latter.

7. The combination with a bolster rail, of a bolster secured to said rail and provided with a cylindrical extension the exterior walls of which are threaded, there being an opening formed in one side of the bolster, a step arranged within the cylindrical extension and provided with spaced disks defining an intermediate oil chamber one of said disks being spaced from the upper edge of the extension to form a cup and provided with an opening forming a source of communication between the cup and oil chamber, a spindle journaled in the step and provided with a whirl disposed at the opening in the bolster, a cap engaging the threads on the extension and forming a support for the step, there being an opening formed in the step to permit the passage of oil from the chamber to the spindle.

8. The combination with a bolster rail, of a bolster secured to the rail and provided with a cylindrical extension the exterior walls of which are threaded, there being an opening formed in one side of the bolster, a step disposed within the cylindrical extension and provided with spaced disks defining an intermediate oil chamber, one of said disks being spaced from the adjacent upper edge of the extension to form a cup and having an opening formed therein forming a source of communication between the cup and oil chamber, a lug depending from the lower disk, a cap engaging the threads on the extension and bearing against the lug, a

packing ring interposed between the lower disk and the cap and surrounding said lug, a spindle journaled in the step and having a whirl rigidly secured thereto and disposed at 5 the opening in the bolster, there being an opening in the step to permit the flow of oil from the chamber to the spindle, a driving shaft, and a friction disk secured to the driving shaft and having its face provided with

a continuous yieldable cushion adapted to 10 bear against the whirl for rotating the spindle.

In testimony that I claim the foregoing as my own, I have hereto affixed my signature in the presence of two witnesses.

WILLIAM TAYLOR NOAH.
